CLAIM

We claim the ornamental design for a flexible garment with symmetrical left and right thumb openings, as shown and described.

DESCRIPTION

FIG. 1 is a front view showing our new design that includes a transparent pocket portion for containing a small portable electronic device;

FIG. 2 is a left side view thereof;

FIG. 3 is a rear view thereof, with a strap portion thereof foreshortened to indicate that it is of indefinite length;

FIG. 4 is a right side view thereof; and,

FIG. 5 is a top view thereof, it being understood that a bottom view would be identical hereto.

Portions broken away or not shown form no part of the claimed design. No appearance feature of any part of the garment located behind a transparent window shown in FIG. 1 is claimed.

Because garments embodying features of the present invention are flexible, those skilled in the art will appreciate that configuration exhibited by the garment is likely to vary depending, at least in part, on how the garment is worn, positioned or supported.
